LADY'S GARMENT

Frances R. McAbee, Westport, Conn., assignor to
 McAbee Industries, Incorporated, Westport,
 Conn., a corporation of Connecticut

Application May 18, 1946, Serial No. 670,796

4 Claims. (Cl. 2—73)

1

This invention relates to ladies' garments having attached waist and skirt portions, and relates more particularly to a structurally and functionally improved undergarment or slip.

An important object of the present invention is to provide a slip designed primarily, though not exclusively, for construction from knitted or other semi-elastic fabrics as distinguished from woven fabrics from which undergarments of this general character are more usually constructed. A garment made from Jersey or other knitted fabric has certain advantages and disadvantages over garments made from woven goods. Among the former is the fact that the garment slides over the shoulders more readily than does the garment made from the less-resilient material. The garment also clings to the body more snugly and produces more flattering lines. A disadvantage in a knitted slip resides in the fact that seam construction is generally unsatisfactory. This is particularly true if patterns used in the construction of woven garments are employed.

Another important object of the present invention is to provide a slip or other like garment formed of knitted or Jersey material wherein all of the seams are straight, with the exception of a curved seam running from the bust-enclosing portion on each side of the garment through the underarm section, the degree of curvature being such, however, that the stitch line can be readily formed by a conventional machine for sewing this type of material.

The garment may be formed from a single blank of material which is joined together along opposed vertical edges to form a single rear vertical seam. The edges of the blank on each side of the garment, which are joined together to form the curved seam just referred to, start at a common point in the bust-encircling section. Each edge may be said to comprise a plane curve having an increasing radius the lower edge starting with a curve forming an arc of a larger circle than does the corresponding section of the upper edge. The two edges start at a common point in the bust-enclosing section and continue 45 downwardly and inwardly toward the front median line of the garment and thence outwardly. As both edges continue towards the rear of the garment, the curves flatten out and may become substantially straight. There is thus cut from the waist section on each side of the garment a generally crescent-shaped portion which continues in a substantially tail-like extension toward the back of the garment.

The garment is thus simply constructed with a minimum of seams. Particularly does it shape the garment for the natural form of the busts, and provides a form-fitting garment which stays in place, regardless of the position or activity of the wearer. In principle, the construction of 60

2

the present garment resembles that of a stocking, and the fitting qualities in the waist section are comparable to the fit of a stocking in the ankle section.

5 In the drawings:

Fig. 1 is a partial front and side elevation of a garment embodying the present invention in position upon the wearer.

Fig. 2 is a partial rear and side elevation of the 10 same.

Fig. 3 is a plan view of the finished garment folded along the front and rear median lines and in substantially flat position, this view showing a garment wherein the rear triangular godet 15 is omitted.

Fig. 4 is a plan view of the main blank used in forming the garment.

Fig. 5 is a plan view of a small triangular godet or insert for the lower rear skirt portion.

20 The garment of the present invention may be formed from a substantially-rectangular piece of Jersey, knitted or other similar material, a plan view of the main blank 10 being shown in Fig. 4. Broken line 11 indicates the front median line of the garment.

25 At its upper end the blank is formed with substantially-straight edges 12 which form the front neckline of the garment, such edges terminating at their upper ends at points 13 to which the front terminals of the shoulder straps 14 may be secured. Continuing from points 13 the upper portion of the blank is defined by concavely-curved edges 15 which merge into substantially-straight edge sections 16 which terminate at points 17. Short, concavely-curved edges 18 complete the upper edge 30 of the blank and terminate at their outer ends at points 19. This upper edge of the garment may be appropriately modified to suit style conditions, etc.

35 Continuing downwardly from points 19 there are substantially-straight edges 22 which terminate at points 23. It will be noted that edges 22 are substantially parallel with the front median line 11. Commencing at points 24 there are downwardly and outwardly-inclined, substantially-straight edges 25 which terminate at points 26. From points 26 there are downwardly-inclined, substantially-straight edges 27 which terminate at their lower ends at points 28. The lower edge of the garment is defined by curved edge sections 29.

45 On each side of the garment there is a cut-out area 32 extending from a point 33 which is located within the bust-enclosing sections of the garment. Each of the edges defining the cut-out area 32 may be said to comprise plane curves having an increasing radius. Thus, the upper edge of the cut-out area comprises a curved edge section 35 which initially extends downwardly and inwardly toward the front median

line 11 of the garment, the curve flattening out, as shown at 36, and terminating at point 23. The lower edge of the cut-out area is defined by a curved edge section 38 which corresponds generally to the arc of a somewhat larger circle than does edge section 35 and extends further inwardly toward the front median line 11. This curve 38 likewise flattens out, as shown at 39, and terminates at point 24. Thus, the cut-out area may be said to be generally crescent-shaped with a tail section extending toward the back of the garment.

The specific location of points 33 defining the upper and inner terminals of cut-out area 32 will vary somewhat, depending upon a number of factors, including the size and shape of the garment. The particular contour of edge sections 35-36 and 38-39 will also vary somewhat, depending upon the particular size of the garment. The total length of edge sections 35-36 is substantially the same as the total length of edge sections 38-39, and in forming the garment after the blank has been constructed in accordance with the foregoing description it is preferred to first join edge sections 35-36 with edge sections 38-39, thus forming a stitch line defined by portions 42 and 43. Although edge sections 35 and 38 are somewhat curved, the curvature is not so great as to prevent effective stitching of these edges together so as to provide a lasting, durable seam. When the edges are thus joined together, points 23 and 24 coincide. The next step is to join edges 22 together to form vertical seam 46, and further, to join edges 25 to form lower vertical seam 47.

If material of the usual width is employed in forming the garment of the present invention, a small triangular godet 50, shown in Fig. 5, may be positioned at the lower rear section of the garment. This godet includes opposed edges 51 and a lower edge 54. Edges 51 are joined to edges 27 to form stitch lines 53. For smaller sizes, however, and also in cases wherein wider material is being employed, the godet may be eliminated, as shown in Fig. 3.

The particular contour of edge sections 35 and 38 which are joined together to form stitch-line section 42 has a decided effect upon the bust-shaping characteristics of the garment. If a more flat-chested garment is, for any reason, desired, these edge sections may comprise a spiral arc somewhat less than 180°. If, on the other hand, a more full-breasted effect is desired, these edge sections may comprise a spiral arc considerably greater than 180°.

While two forms or embodiments of the invention have been shown and described herein for illustrative purposes, and the construction and arrangement incidental to two specific applications thereof have been disclosed and discussed in detail, it is to be understood that the invention is limited neither to the mere details or relative arrangement of parts, nor to its specific embodiments shown herein, but that extensive deviations from the illustrated forms or embodiments of the invention may be made without departing from the principles thereof.

What I claim is:

1. A lady's garment provided with attached waist and skirt portions, two opposed edges of which are joined at the back of the garment, a

seam on each side of the garment extending from a point in the bust-enclosing section, rearwardly through the underarm section to the back of the garment, the edges of the blank which are joined together to form each of such seams comprising plane curves which extend from such point in the bust-enclosing section inwardly toward the front median line of the garment and thence outwardly toward the rear of the garment, the lower edge extending further inwardly toward the front median line than the upper edge.

2. A lady's garment provided with attached waist and skirt portions, two opposed edges of which are joined at the back of the garment, a seam on each side of the garment extending from a point in the bust-enclosing section, rearwardly through the underarm section to the back of the garment, the edges of the blank which are joined together to form each of such seams comprising curved portions which extend from such point in the bust-enclosing section downwardly and inwardly toward the front median line of the garment, and generally straight portions which extend outwardly toward the back of the garment, the curved lower edge portion extending further inwardly and forming the arc of a larger circle than does the curved upper edge portion.

3. A lady's garment provided with attached waist and skirt portions and formed from a blank, two opposed edges of which are joined together to form a rear vertical seam, a seam on each side of the garment extending from a point in the bust-enclosing portion, inwardly through a curved section toward the front median line of the garment and thence outwardly generally parallel with the waist line of the garment, the two edges which are joined together to form such seam being of substantially the same length and terminating at their outer ends at the rear vertical seam, the lower edge extending further towards the front median line and forming the arc of a larger circle than the upper edge.

4. A lady's garment formed from a blank, two opposed edges of which are joined at the rear of the garment to provide attached waist and skirt portions, each side of the waist portion of the blank having a generally crescent-shaped cut-out section terminating in a tail-like extension adjacent the rear of the garment, the edges formed by such cut-out section being joined together to form a seam extending from the bust-enclosing section through the underarm section to the rear of the garment, such edges starting at a common point in the bust-enclosing portion and being curved downwardly and inwardly toward the front median line of the garment and thence outwardly toward the rear of the garment, the lower curved edge section extending further inwardly and forming the arc of a larger circle than the upper curved edge section.
